UNITED STATES PATENT OFFICE.

SAMUEL LIPSIUS, OF NEW YORK, N. Y.

MACHINE FOR PRODUCING RAISED PRINTING.

1,391,743.

Specification of Letters Patent. Patented Sept. 27, 1921.

Application filed March 23, 1920. Serial No. 368,017.

To all whom it may concern:

Be it known that I, SAMUEL LIPSIUS, a citizen of the United States of America, residing at 500 West 176th street, city, county, and State of New York, have invented a new and useful Machine for Producing Raised Printing, of which the following is a specification.

My invention relates in general to a machine for producing raised printing and more particularly to the means for properly applying the powder to a printed sheet.

In general the object is to provide a simple, inexpensive machine for properly treating a printed sheet to produce raised printing or embossed effects.

Another object of my invention is to provide a machine for automatically applying a fusible powder to a printed sheet.

Another object is to provide means for automatically removing the excess powder from the sheet or that which does not adhere to the moist ink.

Another object is to provide means for returning the excess powder removed from the sheet back into the powder distributing receptacle.

Other objects and advantages will appear as the specification proceeds.

In the art of producing raised printing or embossed effects, it is usual to take printed sheets as they come from the press, and before the ink has dried to apply a fusible powder, such as is well known in the art, to the sheets, and then to sharply strike the sheet in order to remove the powder which does not adhere to the moist ink. The sheet with the powder adhering to the ink, is then placed in a heater where the powder and ink amalgamate and swell, and produce the raised printing or embossed effect. The sheet is then cooled after which it is ready for use.

The usual method above outlined presents a number of difficulties. Each sheet must be manually handled by an operative and this hand labor being slow and expensive the cost of the finished product is greatly increased. Part of the powder which is knocked from the sheet is blown about by air currents and is lost. The powder in the air gets on other machines, soils the clothing, and is also breathed by operatives in the shop.

My machine is designed to overcome to a large extent the above difficulties and others.

In the drawings which show merely a preferred form of the invention,

Figure 1 is a side elevation of my machine and showing a fragmentary portion of a heater.

Fig. 2 is a top plan view thereof with the hood removed from the powder distributing receptacle.

Fig. 3 is a section taken in the plane of the line 3—3 of Fig. 2 looking in the direction of the arrows.

Fig. 4 is a detail perspective view of a trough like receptacle for receiving excess powder from a sheet.

Fig. 5 is a fragmentary perspective view of a means for returning the excess powder to the powder distributing receptacle.

On a suitable preferably portable frame 5 is mounted a horizontal conveyer 6. This conveyer may be conveniently formed by providing grooved pulleys 7 and 8 supported on the frame. On these pulleys may be placed suitable conveyer belts 9—9 in the form of cords or other suitable belts. On the frame, I also mount an inclined conveyer 10 which may be conveniently formed by supporting from the frame another grooved pulley 11 and by providing continuous belts over the pulleys 8 and 11. It is to be understood that the conveyer supports may be adjustable as by means of slots such as 12—12 provided in the supports or in the frame.

Adjustably supported from the frame and above one of the conveyers, preferably the horizontal conveyer, is a powder distributing receptacle 13. This receptacle I prefer to make in the form of a cylinder and provided with a mesh or other screen 14 around the surface. This powder distributing receptacle may be supported at one end in a suitable journal, and in the other end may be provided an aperture provided with a suitable tube 15 to return the powder to the powder distributing receptacle as will be hereinafter explained. In order to permit only a portion of the powder distributing receptacle to be operative and to distribute powder, I may provide one or more bands 105 such as 16 around the exterior so as to cause the receptacle to be in effect partially solid or imperforate. The lower end of the tube 15 may be partially removed on one side as shown at 17 to provide a spoon effect for the purpose of picking up the powder and returning the same to the powder distributing

receptacle. About the receptacle 13, there may be provided a hood 18 to prevent the powder from being blown about and contaminating the air. Upon one end of the 5 shaft 19 which rotatably supports the powder distributing receptacle, there may be provided a grooved pulley 20 for a purpose to be hereinafter described.

Beneath the powder distributing receptacle and conveyer, I prefer to provide a substantially trough-like receptacle 21, having converging sides 23 for directing powder to a point at the bottom. Formed integral with, or attached to the trough-like receptacle, there may be provided a channel-like member 23, having a substantially arcuate shape and provided with an upwardly extending lip or projection 24. In the wall 25 of the trough-like receptacle is provided 10 an aperture affording communication between the trough-like receptacle and the channel. A suitable slide or gate 26 may be provided to close this aperture and a wing nut 27, or other suitable means is provided 15 for holding the gate in any desired position.

Adjacent the inclined conveyer, I provide means for vibrating the conveyer. This vibrator may be conveniently formed as follows: Upon an adjustable standard 28 supported from the frame, I provide a plate 29 of press-board, metal, or other suitable material. A wear plate 30 may be provided if desired. Upon an adjustable standard 31 supported from the frame, I may provide 30 a vibrator 32 of any suitable shape, the form shown being a single square block. This vibrator 32 may be rotated by means of the pulley 33, as will be hereinafter described.

Means may be provided for causing a 40 sheet moving up the incline to be firmly engaged by the conveyer. Such means may be conveniently formed by providing upon an adjustable standard a shaft 38' upon which may be journaled one or more sharp 45 edged loose washers 39, adjustably secured against lateral movement by means of set collars such as 39'.

Suitable driving means such as an electric motor 34 will be provided for driving all of 50 the moving parts of my machine. As shown, the shaft 35 of the motor is belted to an idle pulley 36, which is in turn belted to a pulley 37, which drives the conveyers. From the pulley 37, a suitable belt extends to pulley 20 for 55 rotating the powder-distributing receptacle. The shaft 35 of the motor may also be belted to a pulley 33 for driving the vibrator. It is to be understood that separate driving means may be provided for the two conveyers, but I prefer to drive one conveyer, and have the second conveyer driven by the 60 first in order to get a uniform speed in both. Obviously any other suitable arrangement of belts or gears may be provided.

65 Adjacent my machine, I have indicated

a heater 38, which may be of any suitable form, but I prefer to use a heater such as shown in the patents granted to me #1,194,647 August 15, 1916, or #1,261,826, April 9, 1918.

70

Passing around the pulley 7 I have shown suitable belts 40 constituting part of a conveyer from a press (not shown). These belts 40 may pass over a suitable pulley on a press and the printed sheets may be then 75 automatically delivered by the press to the conveyer 6 as will be readily understood.

At times powder may tend to adhere to the trough-like receptacle and for the purpose of causing the powder to descend to 80 the lower part of the receptacle I have shown a tapper or vibrator 41 which may be supported from the frame and driven by the motor 34 if desired.

The operation of my machine is as follows: 85

Printed sheets from a press, before the ink has dried, are brought to my machine either by means of a conveyer or slide chute, or by hand. By whatever means the sheets are brought to the machine, each sheet will go 90 on to the conveyer 6, and since both conveyers, powder distributing receptacle, vibrator and heater are working, the sheet will be carried along beneath the powder distributing receptacle. The powder from 95 said receptacle will fall *en masse*, that is both large and small particles, through the screen and upon the sheet, both where the latter is printed and upon other parts. The powder covered sheet will continue on the 100 conveyer and pass up the incline. If the incline be too steep, or if for other reasons the sheet should tend to slide down, the latter will be caused to engage the conveyer belts by the sharp washers 39, and continue 105 up the incline. Since the vibrator 32 is being operated, the plate 29 which is in proximity to the conveyer, will likewise vibrate the conveyer and sheet, and cause the powder thereon which is not adhering to the 110 moist ink to slide off the sheet, and down into the trough-like receptacle 21 hereinbefore described. The sheet will then pass from the conveyer into the heater 38 where the amalgamation of the ink and powder 115 will take place.

The gate 26 being open, the powder in the trough-like receptacle will slide down into the channel. The tube or arm 15 of the powder distributing receptacle will thus 120 in its passage through the channel pick up the powder, and when the tube gets to an inclined or vertical position, the powder will slide down into the powder distributing receptacle to be used over again.

If it is desired for any reason to use all of the powder from the powder distributing receptacle and not have the surplus returned thereto, the gate 26 may be closed, and there will then of course be no powder in the 130

125

channel for the tube or arm 15 to pick up. The same result may be accomplished by removing the outer end of the tube 15 so that it will not dip into the channel.

- 5 In order to fill the powder distributing receptacle, the powder may be placed in the trough-like receptacle 21, having the gate 26 open, and the machine operated. The powder will thus be automatically carried 10 up and deposited in the powder distributing receptacle.

It will be obvious that a single inclined conveyer could be used in place of the two conveyers shown.

- 15 My machine, being relatively light and portable, may be readily moved about into proximity to a press or a heater.

While I have described in some detail a preferred embodiment of my invention, I 20 do not wish to be limited to the form shown, for the invention may be embodied in various forms coming within the scope of the appended claims.

I claim:

- 25 1. In a device of the character described, a horizontal conveyer and an inclined conveyer adjacent thereto, means for operating said conveyers, a rotatable powder-distributing receptacle supported above and 30 adjacent to one of said conveyers, a hood above said powder receptacle, means for causing a printed sheet to be firmly engaged by and moved by one of said conveyers, means for vibrating said inclined conveyer 35 to cause excess powder on a sheet to fall off, a trough-like receptacle beneath one of said conveyers to receive the powder falling off a sheet, and means for returning the powder from said trough-like receptacle to said 40 powder-distributing receptacle.

2. In a device of the character described, inclined means for conveying a printed sheet to a heater, means for depositing powder on the sheet, and a vibrator for the 45 conveyer to cause excess powder to fall off.

3. In a device of the character described, an inclined conveyer for conveying a printed sheet to a heater, means for depositing powder on the sheet, means for causing said 50 sheet to be engaged by and moved by said conveyer and to prevent said sheet from sliding down the incline, and a vibrator for vibrating the sheet to cause excess powder to fall off.

55 4. In a device of the character described, a conveyer for conveying a printed sheet to a heater, a rotatable powder-distributing receptacle supported above said conveyer, said receptacle being perforated to permit

60 powder therefrom to fall upon the sheet, and means for rotating said receptacle.

5. In a device of the character described, a conveyer for conveying a printed sheet to a heater, a powder-distributing receptacle supported above said conveyer, said recep-

tacle being perforated to permit powder therefrom to fall upon the sheet, means for rotating said receptacle, a trough-like receptacle beneath said conveyer to receive the excess powder falling from said powder-distributing receptacle, and means for conveying the powder from said trough-like receptacle to said powder-distributing receptacle. 70

6. In a device of the character described, 75 an inclined conveyer for conveying a printed sheet to a heater, a powder-distributing receptacle supported adjacent said conveyer, said receptacle being perforated to permit powder therefrom to fall upon 80 the sheet, means for vibrating the conveyer to remove excess powder from the sheet thereon, and a receptacle for receiving said excess powder.

7. In a device of the character described, 85 an inclined conveyer for conveying a printed sheet to a heater, means for depositing powder upon said sheet, a plate supported beneath and adjacent to said conveyer, and means for vibrating said plate 90 to cause the conveyer and sheet to be vibrated to remove the excess powder from the sheet.

8. In a device of the character described, 95 a conveyer for conveying a printed sheet to a heater, a powder-distributing receptacle supported above said conveyer, part of said receptacle comprising a screen to permit powder to pass therethrough and fall upon the sheet, a trough-like receptacle 100 supported beneath said conveyer to receive the excess powder from said powder-distributing receptacle, and a mechanical conveyer for returning said excess powder to the powder-distributing receptacle. 105

9. In a device of the character described, a conveyer for conveying a sheet to a heater, a powder-distributing receptacle supported above said conveyer and adapted to permit powder to fall upon the sheet, a trough-like 110 receptacle supported beneath said conveyer to receive the excess powder from said distributing receptacle, a channel communicating with said trough-like receptacle into which powder from the trough-like receptacle flows, and a mechanical conveyer for conveying powder from said channel back into said powder-distributing receptacle. 115

10. In a combination such as set forth in claim 9, said mechanical conveyer for 120 conveying powder comprising an arm dipping into said channel and serving to convey powder to said distributing receptacle when the latter is rotated.

11. In a combination such as set forth 125 in claim 9, and a movable gate between said trough-like receptacle and said channel for closing communication between said parts.

12. In a device of the character described, means for conveying a printed sheet to a 130

4
heater, a powder distributing receptacle for permitting powder to fall upon the sheet, said receptacle including a perforated screen and means for covering a part of 5 said screen so as to permit powder to pass through only a predetermined portion thereof.

13. In a device of the character described, a conveyer for a sheet, an inclined conveyer 10 adjacent said first named conveyer, a powder distributing receptacle above one of said conveyers and means for varying the inclination of said inclined conveyer.

14. In a device of the character described, 15 a frame carrying a conveyer for a printed sheet, a conveyer for conveying sheets from a press to said first mentioned conveyer, a rotatable powder distributing receptacle above said first mentioned conveyer to permit 20 powder to fall upon the sheet, means for removing excess powder from the sheet and means for receiving said excess powder.

15. In a device of the character described, a conveyer for a printed sheet, a powder

distributing receptacle above said conveyer, 25 a trough like receptacle having an inclined wall beneath said conveyer for receiving excess powder falling from said powder distributing receptacle, and means for vibrating 30 said trough like receptacle.

16. In a device of the character described, a conveyer for conveying a sheet to a heater, a powder distributing receptacle supported above said conveyer and adapted to permit powder to fall upon the sheet, a trough-like 35 receptacle supported beneath said conveyer to receive said excess powder from said distributing receptacle, and a mechanical conveyer for conveying powder from said trough-like receptacle back into said powder 40 distributing receptacle.

17. In a combination such as set forth in claim 16, said conveyer comprising a movable arm for receiving powder from the trough-like receptacle and returning it to 45 said distributing receptacle.

SAMUEL LIPSIUS.
